LIGHTNING-ROD CABLE.

1,135,940.

Specification of Letters Patent. Patented Apr. 13, 1915.

Application filed April 5, 1912. Serial No. 688,819.

To all whom it may concern:

Be it known that I, PETER J. JUEL, a citizen of the United States, and a resident of Council Bluffs, in the county of Pottawattamie and State of Iowa, have invented certain new and useful Improvements in Lightning-Rod Cables, of which the following is a specification.

My invention relates to electrical conductors, and more especially to cables for use in lightning protection.

It is the object of my invention to provide a cable for this purpose which will have a large surface proportionally to its weight or the amount of material employed in its construction, and having sufficient flexibility and tensile strength to amply meet the practical requirements for an article of this kind.

20 A construction embodying my invention is illustrated in the accompanying drawings, in which—

Figure 1 is a side view of a piece of the cable having the several layers thereof successively broken away to show the other layers disposed within them, and Fig. 2 is a transverse sectional view of the cable.

It is well known that lightning is a disruptive electrical discharge which causes in 30 the conductors through which it passes an alternating or pulsating current of enormously high frequency. It is also known that the carrying capacity of conductors for electrical currents of this nature is proportional almost entirely to the surface area 35 rather than to the sectional area of the conductor. It is therefore desirable in a conductor for this purpose that the same shall have a large surface, and in order that a 40 large surface may be provided with the greatest economy of material it is necessary that for the inner part of the conductor there shall be used the least amount of material consistent with a suitable tensile strength 45 and lateral stability. It is also desirable that the external part of the conductor shall present a practically continuous surface and yet be so divided that it will be flexible.

In a cable constructed in accordance with 50 my invention there are two principal parts, differing considerably from each other in their structure. These parts are the outer covering or sheath portion, and the inner or core portion of the cable. The cable as a 55 whole comprises a number of concentric

layers, each consisting of helically extending wires, all preferably of a metal, such as copper, having high conductivity.

In the construction shown in the drawings the central or innermost portion of the cable 60 is a strand formed by a pair of wires 1 twisted together so that each assumes the form of a helix, the helices being about a common axis. Around the core-center or strand formed by the wires 1 are disposed a 65 pair of wires 2, which extend helically around the said core-center. The direction of twist or of advance of the helices formed by the wires 2 is opposite to that of the wires 1, and the wires 2 are spaced apart so that 70 they are not in contact with each other, the pitch of the helices being large proportionally to the diameter of the wires. The said wires 2 form what may be termed the second layer of the cable-core. The third layer 75 is formed by a pair of wires 3, spaced apart and extending helically, the direction of the helices being opposite to those of the wires 2, or in the same direction as those of the wires 1. The fourth layer is similarly 80 formed and consists of a pair of wires 4, the direction of twist therein being the same as that of the wires 2. The fifth layer 85 comprises two pairs of wires 5, which are also spaced apart and disposed helically, the direction of the helices being the same as those of the wires 1 and 3.

The structure thus far described and comprising the core-center or strand formed by the wires 1, and the four concentric layers 90 formed by the wires 2, 3, 4 and 5, is the cable-core. Obviously, it may consist of any desired number of layers of wire, and each layer may be formed by a suitable number of individual wires. It is preferable that as 95 the diameter of the layers becomes greater the number of individual wires used in forming the layer be increased, though it is not necessary to maintain an exact proportion between the diameter of the layer and 100 the number of wires used in forming it. It should be especially noted that, except for the wires forming the core-center, the wires of any one layer of the core do not come in contact with each other but only with the 105 wires of the adjoining layers inside and outside of the layer considered.

The exterior or sheath of the cable is formed by a plurality of strands 6, each strand being formed by a pair of wires 7 110

twisted together, and the several strands being disposed helically around the core, the helices being opposite in direction to those of the outer layer of the core. The number 5 of strands in the sheath, their size, and the pitch of the helices are such that the several strands lie in contact with each other and thus present a practically continuous surface at the outside of the cable.

10 From the foregoing it will be obvious that my invention provides a cable peculiarly adapted for the purpose set forth. By the alternately reversed direction of twist in the several layers of the core and the spacing 15 apart of the wires of each layer, the same are caused to occupy a large space proportional to the actual cross-section of the metal used. Thus in the structure shown in the drawings, while the sectional area of the 20 space occupied by the core is nearly as large as that occupied by the sheath, there are employed in the core only twelve wires, while in the sheath there are twenty-eight wires or fourteen strands of two wires each. The 25 cable thus presents a structure combining economy of material and light weight, with large surface area, high conductivity, flexibility, and tensile strength sufficient for the practical requirements of an article of the 30 kind.

Now, having described my invention, what I claim and desire to secure by Letters Patent is:

35 1. In a lightning-rod cable, a core comprising a central strand, and a plurality of concentric layers of wires twisted around

said central strand, each layer comprising a plurality of helically-extending wires spaced apart laterally so that no two wires of the same layer are in contact with each 40 other, the direction of the helices being opposite in adjoining layers, and a sheath comprising a plurality of helical multiple-wire strands twisted about the core in a direction opposite to that of the wires in the outer 45 layer of the core, and each strand contacting laterally with the strands adjoining it.

2. In a lightning-rod cable, a core comprising a central strand consisting of two wires twisted together to form contacting 50 helices, and a plurality of concentric layers of wires twisted around said central strand, each layer comprising a plurality of helically-extending wires spaced apart laterally so that no two wires of the same layer are 55 in contact with each other, the direction of the helices being opposite in adjoining layers, and a sheath comprising a plurality of helical strands twisted about the core in a direction opposite to that of the wires in 60 the outer layer of the core, each strand of the sheath consisting of two wires twisted together, and each strand of the sheath being in contact with the strands at each side thereof. 65

In testimony whereof I have hereunto subscribed my name in the presence of two witnesses.

PETER J. JUEI.
